US00D746700S

(12) **United States Design Patent**
Boehnen et al.(10) **Patent No.:** **US D746,700 S**
(45) **Date of Patent:** **** Jan. 5, 2016**(54) **HANDLE PACKAGING**

- (71) Applicant: **LIBERTY HARDWARE MFG. CORP.**, Winston-Salem, NC (US)
- (72) Inventors: **Patrick Boehnen**, Summerfield, NC (US); **Christine Lemnios**, Greensboro, NC (US)
- (73) Assignee: **LIBERTY HARDWARE MFG. CORP.**, Winston-Salem, NC (US)
- (**) Term: **14 Years**
- (21) Appl. No.: **29/491,473**
- (22) Filed: **May 21, 2014**
